UNITED STATES PATENT OFFICE

WILLIAM A. LORENZ AND EDWARD E. CLAUSSEN, OF HARTFORD, CONNECTICUT, ASSIGNORS TO FELIX W. LEINBACH AND CLARENCE A. WOLLE, OF BETHLEHEM, PENNSYLVANIA.

PAPER-BAG MACHINE.

SPECIFICATION forming part of Letters Patent No. 410,841, dated September 10, 1889.

Application filed December 10, 1888. Serial No. 293,110. (No model.)

To all whom it may concern:

Be it known that we, WILLIAM A. LORENZ and EDWARD E. CLAUSSEN, of Hartford, Connecticut, have jointly invented certain new and useful Improvements in Paper-Bag Machines, of which the following description and claims constitute the specification, and which is illustrated by the accompanying six sheets of drawings.

10 These improvements are particularly applicable to the paper-bag machine which is shown in Letters Patent of the United States, No. 361,951, to Lorenz and Honiss, of April 26, 1887, and they consist in mechanism to make 15 the "diamond" fold described in that patent, and in mechanism for delivering the diamond-fold blank from one traveling folding-bed to another.

Figures 1, 2, and 3 of the drawings are a 20 plan, a side, and an end view, respectively, of a portion of a tucked paper-tube, which is called by us a "blank." Fig. 4 is a side view of this blank pressed together near its center. Figs. 5 and 6 are a side and a plan view of the 25 blank, showing one end opened up into a box-like form. Figs. 7 and 8 are a side and a plan view of the blank, showing the box-like form partly folded down into the shape which we term the "diamond." Figs. 9 and 10 are a 30 side and a plan view of the same, fully folded down. Fig. 11 is a plan of the machine. Fig. 12 is partly a side view thereof and partly a vertical section on the line *a b* of Fig. 11. Fig. 13 is a rear end view of the left-hand portion 35 of Figs. 11 and 12, looking from left to right. Fig. 14 is a side view of portions of Fig. 12, with a bag folded into the box-like form. Figs. 15 and 16 are a plan and a side view, respectively, of the upper portion of the machine, 40 showing the bag folded into the diamond form. Figs. 17 and 18 are a side and an end view of a modified form of the diamond-folding mechanism. Figs. 19 and 20 are an end and a side view of another such modification. Figs. 21 45 and 22 show the same modification in another position.

For greater clearness, the gears 36, 37, 38, and 39 are not shown in full in side view, but have teeth omitted.

50 The numeral 1 indicates a bag-blank sev-

ered from a continuous tucked paper-tube, and having two inwardly-projecting tucks 2 and 3, and longitudinal slits 4 and 5, a lip 6, a corresponding recess 7, the tucks extending the entire length of the blank, and the slits 55 extending only a short distance into one end thereof, as shown in Figs. 1 and 3. The form which we call the "box" is that shown in Figs. 5 and 6, and is marked with the numeral 8. The form which we call the "diamond" 60 is that shown in Figs. 7 to 10, and is marked with the numeral 9.

In this machine a blank is being delivered to a traveling folding-bed and the box form is first folded, then the diamond form is 65 delivered, and then the partly-folded bag is delivered to another traveling folding-bed, where subsequent operations may be performed thereon.

The two traveling folding-beds are made 70 in the form of a rocking carriage and a revolving cylinder, respectively, and are similar to the two beds shown and described in said Letters Patent No. 361,951; but in that patent there is shown intermediate rolls that 75 grip and pass the bag from the first to the second bed, while in this machine these intermediate rolls are omitted. The rocking carriage has three mechanisms attached to it, which are similar in form and in operation to 80 those described in said Letters Patent No. 361,951, and they compose a presser-plate mechanism, a tuck-entering mechanism, and a blade-folding mechanism, and the carriage itself is oscillated by a crank and connecting- 85 rod, as shown in that patent.

The carriage is indicated by the numeral 80, is pivoted on a shaft 81, and is worked forward and backward by a connecting-rod 78. Upon the upper part of the carriage 80 90 there is a presser-plate 98, secured to two brackets 100 and 101, which brackets receive vertical motion from two presser-arms 102 and 103, which are fixed to a rocking shaft 104, and which carry pins 105 and 106, which 95 enter the brackets 100 and 101. To the lower end of the bracket 100 a link 107 is attached, and is pivoted at 108 to the carriage, and gives the presser-plate a parallel motion. To the shaft 104, at the outer end of the car- 100

riage 80, there is attached an arm 109, to which is pivoted a connecting-rod 110, which receives motion like that shown in said Letters Patent No. 361,951.

5 The carriage 80 has two ears 118 and 119, carrying fixed studs 120 and 121, upon which are placed the two rocking tuck-levers 122 and 123, carrying cam-rolls 126 and 127, which run in cam-grooves 128 and 129 of cams 130 and 131, which cams are attached to the gears 85 and 86, running upon the shaft 81 at both sides of the carriage 80. To the upper end of these tuck-levers 122 and 123 are secured tuck-blades 132 and 133, which have angular 15 ends projecting inwardly toward the center of the machine, and these blades receive a reciprocating motion in and out from the carriage 80 as the cams 130 and 131 revolve.

In the upper ends of the tuck-levers 122 and 123 are placed two shafts 134 and 135, to which are secured box-blades 136 and 137, which also have angular ends. These blades 136 and 137 are operatively connected with a cam on the shaft 81, and receive therefrom a 25 rotary reciprocating motion of about one hundred and eighty degrees, as shown in Figs. 11 and 16, respectively. This movement is attained by means of pinions 138 and 139, fixed on the box-blade shafts 134 and 135 and 30 driven by the racks 140 and 141, which slide in casings attached to the upper ends of the tuck-levers. These racks are operated by means of connecting-rods 142 and 143, which are connected at the pivots 144 and 145 to oscillating levers 146 and 147. These oscillating levers swing upon the hubs of the tuck-levers 122 and 123, which oscillate upon the studs 120 and 121. The opposite ends of the 35 oscillating levers 146 and 147 are bevel-sector, which mesh into bevel-sector arms 148 and 149, fastened to the shaft 150, which oscillates in ears in the carriage 80.

To the outer end of the shaft 150 is secured the arm 151, carrying a pin 152, upon which 45 a roller 153 revolves, engaging in a cam-groove 154 in the cam 155, which cam is fixed to the other cam 130 and revolves with it, thus transmitting an oscillating motion simultaneously to the arms 146 and 147, and through them 50 giving oscillating motion to the box-blades 136 and 137. The tuck-levers 122 and 123 and the levers 146 and 147 are all held upon the studs 120 and 121 by the collars 156 and 157. The tuck-levers 122 and 123 receive the 55 proper oscillating motion from the cams 130 and 131 at suitable intervals, thus driving the blades attached to their upper ends to and from the carriage. The levers 146 and 147 also receive a proper oscillating motion from 60 the cam 155 at suitable intervals, transmitting an oscillating motion to the box-blades 136 and 137, all of which motions occur during the rocking motion of the carriage 80.

The new mechanism for folding the box-like form into the diamond form is as follows: 65 Arranged on the upper part of the carriage 80 are two side plates 10 and 11, secured to

shafts 12 and 13 in brackets 14 and 15, which are fastened to the carriage. On the shafts 12 and 13 are two bevel sector-pinions 16 and 17, meshing into bevel sector-arms 20 and 21. These arms are fixed to a cross-shaft 18, and from the arm 21 a stud 22 projects and is pivoted to the connecting-rod 23, the other end of which is pivoted by the pin 24 to the side 75 lever 25, which is pivoted to a stud 26 in the carriage 80. The lower end of the lever 25 is marked 27, and has a projection which enters a cam-groove 28 of the cam 29, which is fixed to the shaft 81. The side plates 10 and 11 receive the proper oscillating motion simultaneously from the cam 29 at suitable intervals, thus driving the plates through an arc of about ninety degrees from the position shown in Figs. 11, 12, and 13 to that shown in Figs. 85 15 and 16.

The cylinder 32 is secured to a shaft 33, which revolves in bearings 45 and 46, which are part of the uprights 34 and 35. The shaft 33 is driven by means of a gear 36, which derives motion from a gear 37 on the shaft 81, and the timing is so arranged that the cylinder 32 makes one revolution to two oscillations of the carriage 80. The object of this is to work two sets of gripping devices on the 95 cylinder; but one set may be employed, if preferred, and the cylinder may be correspondingly reduced in diameter. The new mechanism for delivering the diamond-fold blank to the cylinder is as follows: 100 Fastened to the uprights 34 and 35 are two rods 41 and 42, which hold two plates 43 and 44 over the cylinder. Upon the projecting hubs 45 and 46 of the uprights are fixed two cams 49 and 48, respectively. The cam 49 is 105 provided with the cam-groove 50, which works the arms 51 and 52, the shafts 53 and 54, and the lower grippers 55 and 56. These shafts are on opposite sides of the cylinder, and these grippers have bifurcated ends 57, which rise 110 beyond the surface of the cylinder and fall back even with that surface. The cam 48 is provided with the opposite cam ends 58 and 59, the contours of which ends are shown by dotted lines in Fig. 12, and those cam ends 115 alternately lift the arms 60 and 61 against the resistance of the springs 62 and 63, respectively, and thus work the shafts 64 and 65, together with the grippers 66 and 67, fixed thereto, and these springs press the ends 68 120 of the upper grippers 66 and 67 down upon the ends 57 of the lower grippers 55 and 56, whenever neither of the said cam-ends is lifting the upper grippers.

The operation of this machine is as follows: 125 As bag-blank 1, having been fed into the upper part of the carriage 80 and gripped by the presser-plate 98, and the two pairs of blades 134 and 136 and 133 and 137 having entered the tuck-recesses 2 and 3 of the blank, as shown in Figs. 11 and 12, and the two blades 136 and 137 having been oscillated about one hundred and eighty degrees, as shown in Fig. 14, a box-like form 8 will have been folded up in 130

the same manner as that shown in said Letters Patent No. 361,951. The side plates 10 and 11 then fold down from the position shown in Fig. 14 to that of Figs. 15 and 16, and thus 5 fold the box-like form 8 into the diamond form 9. The front end of the diamond form is then carried forward by the carriage 80 and inserted between the ends 57 and 68 of the grippers 55 and 56, and then the upper gripper 68 is forced by the spring 62 down upon the forward end of the diamond form, thus gripping the bag-blank firmly, as shown in Figs. 15 and 16. The various blades attached to the carriage then release the bag-blank, the 15 side plates 10 and 11 rise to their upper position, and the bag-blank is drawn forward upon the cylinder 32. Meanwhile the lower gripper 55, followed by the upper gripper 66, is dropped to the level of the cylinder-surface, 20 so that the bag may lie upon it, and the diamond-folded bag-blank is drawn by the grippers 55 and 66 under plates 43 and 44, to preserve its folded flatness and to aid in holding it down upon the cylinder. Thus delivered 25 to the cylinder the bag-blank may be operated upon, as in said Letters Patent No. 361,951.

A modified form of gearing for working the side plates 10 and 11 is shown in Figs. 17 and 18. Here the side plates are attached to shafts 30 12 and 13, rocking in brackets 14 and 15, and secured to the shafts 12 and 13 are sector-pinnions 90 and 91, meshing into racks 88 and 89, sliding in brackets 14 and 15. Meshing at right angles into these racks are sector-gears 35 85 and 86, fastened to a cross shaft 18, to which an arm 87 is also secured. At the end of this arm, on a pin 92, is attached the connecting-rod 23, which derives motion in a manner similar to that before described. Other methods 40 of connecting the parts together may also be employed.

A modified form of side plates is shown in Figs. 19 to 22. Here the two side plates 158 and 159 are hung over the top of the carriage 45 80, the plates being supported and swung on studs 160 and 161, these latter being fastened in brackets 162 and 163, which are projections of the carriage 80. Fastened to the side plates 158 and 159 are two bevel-sectors 164 50 and 165, which engage with sector-arms 166 and 167, which are secured to a cross-shaft 168, which is also supported in bearings in

the brackets 162 and 163. Oscillating motion is given to the plates through the sectors by means of a rod 169 on the stud 170, which 55 stud is driven into the sector 167. The rod 169 derives its motion in the same manner and at the same time that the rod 23 does. In Figs. 19 and 20 the bag is shown folded as far as the box-like form 8, the side plates 60 158 and 159 being swung open, and in Figs. 21 and 22 the side plates are swung in, converting the box-like form 8 into the diamond form 9.

We claim as our joint invention—

1. The combination of the rocking carriage 80, the side plates 10 and 11, rocking toward each other above that carriage and at right angles to the rocking thereof, and the cam 29, and mechanism, substantially as described, 7c between that cam and those side plates and operating to work the latter, all substantially as described.

2. The combination, in a bag-machine, of the folding-bed thereof, and a pair of grippers 75 pivoted in a recess in the surface of that bed and rising from that surface to clasp a bag-blank some distance above it, and then falling to that surface to carry that blank thereto, all substantially as described and shown. 80

3. The combination of the cylinder 32, the pair of grippers 55 and 66, rocking in a recess in the periphery of that cylinder upon the shafts 53 and 64, the arms 51 and 60, rocking those shafts, and the cams 49 and 48 and the 85 spring 62, working those arms, all substantially as described.

4. The combination of the cylinder 32, the pair of grippers 55 and 66, rocking in a recess in the periphery of that cylinder upon the 90 shafts 53 and 64, the arms 51 and 60, rocking those shafts, the cams 49 and 48 and the spring 62, working those arms, and the plates 43 and 44, co-operating with the grippers 55 and 66 to draw and hold a bag-blank down 95 upon the periphery of the cylinder, all substantially as described.

Hartford, Connecticut, December 6, 1888.
